UNITED STATES PATENT OFFICE.

GEORGE WASHINGTON TOLER, OF GREENVILLE, ARKANSAS.

CULTIVATOR.

SPECIFICATION forming part of Letters Patent No. 715,178, dated December 2, 1902.

Application filed December 5, 1901. Serial No. 84,791. (No model.)

To all whom it may concern:

Be it known that I, GEORGE WASHINGTON TOLER, a citizen of the United States, residing at Greenville, in the county of Yell and State of Arkansas, have invented a new and useful Cultivator, of which the following is a specification.

This invention relates to cultivators.

The object is to present a cultivator for use in cultivating corn, cotton, or the like in which provision shall be made to cause effective removal of weeds, grass, &c., and for supplying clean earth to the furrow, at the same time breaking up or dividing the earth, thereby to prevent baking, to provide suitable means by which the disks or cutters and also a roller used in connection with the device may be held at the predetermined or desired adjustment, to provide means by which the scraper may be adjusted with relation to the disks or to the roller independently of either, and generally to provide a simple, thoroughly effective, and durable form of cultivator.

The invention consists in the novel construction and combination of parts of a cultivator, which will be hereinafter fully described and claimed.

Generally stated, the cultivator characterized by my invention comprises, in connection with a wheel-supporting frame, two sets of disks oppositely convexed with relation to each other, the disks being adjustable about a vertical axis at right angles to their supports, a scraper arranged in front of each set of disks and adjustable with relation thereto, thereby to cause the scraper to be rendered coöoperative with the disks irrespective of the character of furrow cut, and a roller arranged at the rear of the disks and adjustable independently of the disks and the scrapers, the object of the roller being to overcome side draft and to press down the loose earth, thereby to retain moisture.

In the general construction of the cultivator the supporting-frame and adjuncts usually appertaining thereto may be of any preferred construction and therefore need no specific description.

The invention resides in the coöoperative relation effected between the scrapers, the disks, and the rollers and the means by which either or all of these may be adjusted

independently to render the device thoroughly operative under all circumstances.

In the accompanying drawings, forming a part of this specification, in which like numerals of reference indicate corresponding parts, I illustrate a form of embodiment of the invention, it being understood that some of the ideas may be carried into effect in other ways without departing from the spirit of the invention.

In the drawings, Figure 1 is a view in perspective, taken from the rear of the machine. Fig. 2 is a view in side elevation. Fig. 3 is a view in plan. Fig. 4 is a detail view of one of the scrapers. Fig. 5 is a detail perspective view of the disk-carrying yoke and the roller-carrying yoke, showing the clutch mechanism for holding the two yokes in adjusted position with relation to the supporting-frame. Fig. 6 is a longitudinal sectional detail view of the disk-carrying yoke.

Referring to the drawings, 1 designates an arch, and 2 an axle, the latter carrying supporting-wheels 3, as usual. The axle may support the tongue, seat, and other parts common to the frame of an ordinary cultivator, and as these form no part of the present invention description is deemed unnecessary.

The supporting-frame of the cultivator mechanism comprises two beams or bars 4, suitably secured to the arch 1, and as the mechanism carried by each bar is the same a description of one will serve for both.

Working in a suitable guide 5 on the beam 4 is a standard 6, carrying a scraper 7, the scraper being, in effect, an ordinary mold-board without a landside. In other words, in operation it performs the function of a scraper pure and simple and not that of a plowshare. The scraper is secured to the standard at an angle to the bar, as usual, and is mounted for adjustment in the arc of a circle—that is to say, is capable of a vertical tilting adjustment transversely of the device—thus to cause the cutting edge of the scraper either to lie parallel to the ground or at an angle thereto. To effect this, the scraper is provided with a series of openings 8, arranged in the arc of a circle, a bolt 9, passing through one of the openings, serving to hold the scraper in the desired adjustment. Normally the inner edge of the scraper is at an

angle to the faces of the disks, so that the grass, weeds, or the like detached by the scraper will be thrown to one side. It will be observed that in addition to the series of 5 openings 8 there are two other openings 10, one of which is permanently engaged by a bolt 11 when the scraper is adjusted for ordinary use; but should it be desired to bring the inner edge of the scraper parallel with 10 the standard the bolt 11 will be removed from the opening shown and the scraper moved to one side to bring the other opening opposite that in the standard, and the bolt 11 may again be inserted, and the scraper thus 15 held in its adjusted position. The standard is provided with a plurality of openings 12 to be engaged by a bolt 13, passing through the guide on the side of the standard, this arrangement being provided for effecting 20 vertical adjustment of the scraper. On the opposite side of the beam to that occupied by the standard 6 is another guide 14, engaged by a standard 15, the lower portion of which is bent approximately at right angles to its 25 length and supports the disk-carrying yoke 16. The standard 15 is provided with a plurality of openings 17 to be engaged by a bolt 18, carried by the guide 14, this arrangement being employed to effect the vertical 30 adjustment of the disks irrespective of the scraper. The manner of connection between the yoke 16 and the standard 15 is to be such that when the yoke is adjusted to cause the disks to occupy the desired angle with 35 relation to the furrows the yoke will be held in this position. Several forms of device may be employed for this purpose, and that shown herein is illustrative of one arrangement that will be effective in operation 40 and readily applied for use. It consists in providing the bottom of the standard with a serrated face 19 to engage with a similar face 20 on the upper surface of the yoke, a bolt 21 passing through the lower portion of the 45 standard 15 and the yoke to clamp these two serrated surfaces together. It will be observed by reference to Fig. 3 that the yoke 16 is provided with a plurality of openings 22, each opening being surrounded by one of 50 the serrated faces 20, above referred to. By this arrangement when the yoke is moved to the desired angle it will be firmly held in position against shifting. On the inner side of 55 the bar is secured a fender 23, the function of which is to prevent the disks in operation from covering up the small corn or cotton.

Carried by the yoke 16 is an arm 24, which may be slightly resilient, this arm to be fixed to the yoke 16 in such manner as to move 60 therewith. The arm 24 carries a yoke 25, provided with a plurality of openings 26 to be engaged by a bolt 27, the manner of holding the yoke 25 in rigid connection with the arm 24 being preferably similar to that described in connection with the holding of the yoke 16 rigid with the standard 15. The yoke 25 carries a roller 28, the function of

which is to press down the loose dirt that has been cut up by the disk, thereby to prevent escape of moisture.

In the operation of the device the scraper-blade scrapes and loosens the surface of the soil and at the same time cuts and sheds the vegetation toward the outer side of the device, so as not to choke the harrow-disks 75 which are tracked in rear of the scraper and act to cut or chop the loosened soil, and finally the roller 28 passes over the finely-pulverized soil, so as to pack or press the same and thereby prevent the escape of moisture. 80

It will now be understood that the present device is intended to break up and pulverize a comparatively thin surface layer of the soil, and for this reason employs a gang or plurality of comparatively small disks which travel 85 in the track of the scraper and act upon the soil which has been loosened by the scraper, wherefore it will be understood that the device is not intended for and is also incapable of turning a furrow, but is arranged to break 90 up or pulverize a thin surface layer of soil.

In some sections of the country where there is what is known as "black-wax" land—that is to say, a soil that is heavy and sticky—the scraper may be removed and a second series 95 of disks, carried by a suitable standard, be placed in front of the usual disks and held in place by the guide occupied normally by the scraper. It will be understood that the disks will be oppositely convexed, so that 100 one set of disks will throw the earth from the cotton or the like and the other to the cotton or the like, the fender in the manner described preventing any covering up of the cotton or corn.

It will be observed by the manner in which the different parts are assembled with relation to the supporting-frame that each part is adjustable independently of the other, and by this manner of arrangement all conditions 110 arising in the use of such a cultivator will be provided for.

Although not shown in the drawings, I contemplate providing scrapers to remove accumulations of soil from the disks and the 115 covering-rollers when the cultivator is being used upon heavy and sticky soil, said scrapers to be of any well-known or preferred form.

What I claim is—

1. The combination with a frame, of a yoke 120 disposed transversely thereof, a gang of disks carried between the ends of the yoke, an arm carried by and projected rearwardly from the yoke, a second yoke carried transversely by the rear end portion of the arm, and a coverer 125 mounted between the opposite end portions of the last-mentioned yoke.

2. The combination with a frame, of a vertically-tiltable yoke disposed transversely thereof, a gang of disks carried by the yoke, 130 an arm carried by and projected rearwardly from the yoke, an inverted substantially U-shaped yoke carried by the arm and adjustable endwise in an arcuate path, and a cov-

erer carried between the opposite end portions of the **U**-shaped yoke.

3. The combination with a frame, of an inverted substantially **U**-shaped yoke disposed 5 transversely thereof and adjustable endwise in an arcuate path, a gang of disks carried between the opposite end portions of the yoke, an arm carried by and projected rearwardly from the yoke, a second inverted substantially **U**-shaped yoke carried by the rear portion of the arm and adjustable endwise in an arcuate path upon the arm as a support, and a coverer carried between the opposite end portions of the last-mentioned yoke.

15 4. In a cultivator, the combination with a supporting-frame, of a standard adjustably connected with the frame, the lower end of the standard being provided with a serrated boss, a yoke provided with a plurality of openings each surrounded by a serrated boss, any one of the bosses on the yoke being adapted to be clamped into engagement with the boss on the lower end of the standard, disks supported by the yoke, and an arm carried by 20 the yoke, a roller-carrying yoke secured to the arm and provided with serrated bosses to be locked into engagement with the arm to hold the roller in the desired adjustment.

5. In a cultivator, the combination with the 30 frame thereof, of an upstanding scraper-blade disposed transversely of the frame and inclined rearwardly to shed vegetation, a transverse shaft hung from the frame in rear of the scraper, rotatable harrow-disks mounted 35 upon the shaft and tracked in rear of the scraper to pulverize the soil loosened thereby, and a fender having its upper forward end connected to the frame and inclined downwardly and rearwardly and offset laterally to 40 lie across the inner end of the disks.

6. In a cultivator, the combination with a support, of a yoke hung therefrom and provided with a series of openings, a fastening for interchangeable engagement with the 45 openings to adjustably connect the yoke with the support, a shaft supported within the yoke,

disks mounted upon the shaft, a depending arm carried by and projected rearwardly from the yoke, and an adjustable coverer carried by the rear end of the arm.

7. In a cultivator, the combination with a support, of an arm carried thereby and projected rearwardly therefrom, a yoke having a series of perforations, a fastening for interchangeable engagement with the openings to 55 adjustably connect the yoke to the arm, and a covering-roller journaled between the opposite ends of the yoke.

8. In a cultivator, the combination with the frame thereof, of an upstanding scraper-blade 60 disposed transversely of the frame and inclined rearwardly to shed vegetation, a transverse shaft hung from the frame in rear of the scraper-blade, rotatable harrow-disks mounted upon the shaft and tracked in rear 65 of the scraper to pulverize the soil loosened thereby, and a roller tracked in rear of the disks to press down the pulverized soil.

9. In a cultivator, the combination with the frame thereof, of an upstanding scraper-blade 70 hung from the frame and inclined rearwardly to shed vegetation, a yoke hung intermediate of its ends from the frame and disposed transversely thereof in rear of the scraper-blade, a shaft carried between the ends of the yoke, 75 rotatable harrow-disks mounted upon the shaft and tracked in rear of the scraper-blade to pulverize the soil loosened thereby, an arm carried by and projected rearwardly from the yoke, another yoke carried by the rear end 80 of the arm and disposed transversely of the frame, and a roller journaled between the opposite ends of the yoke and tracked in rear of the disks to press down the pulverized soil.

In testimony that I claim the foregoing as 85 my own I have hereto affixed my signature in the presence of two witnesses.

GEORGE WASHINGTON TOLER.
